UNITED STATES PATENT OFFICE.

JOSEPH T. BOND, OF SPENCERVILLE, MARYLAND, ASSIGNOR TO PURITY PAPER BOTTLE CORPORATION, OF WASHINGTON, DISTRICT OF COLUMBIA.

MEANS FOR FORMING CLOSURES OR CAPS FOR RECEPTACLES.

1,047,373.

Specification of Letters Patent.

Patented Dec. 17, 1912.

Application filed January 6, 1911. Serial No. 801,227.

To all whom it may concern:

Be it known that I, JOSEPH T. BOND, a citizen of the United States, residing at Spencerville, in the county of Montgomery 5 and State of Maryland, have invented certain new and useful Improvements in Means for Forming Closures or Caps for Receptacles; and I do hereby declare the following to be a full, clear, and exact description 10 of the invention, such as will enable others skilled in the art to which it appertains to make and use the same.

My invention relates primarily to paper or similar receptacles, has especial reference 15 to means for forming closures or caps for receptacles, has for its object economy in manufacture, and consists in certain improvements, which will be fully disclosed in the following specification and claims.

20 In the accompanying drawings, which form part of this specification:—Figure 1 represents a vertical transverse section, partly in elevation showing the parts of the machine in position after the blank has been 25 cut from the stock. Fig. 2 is a like view showing the parts in position at the end of the closure forming stroke. Fig. 3 is a like view showing the parts separated at the end of the up or return stroke, with a closure 30 blank formed and displaced from the face of the forming-die, and Fig. 4 is a like view, showing the closure blank displaced from the position shown in Fig. 3.

Reference being had to the drawings and 35 the designating characters thereon, the numeral 1 indicates the bolster-plate. 2 the bolster provided with a heating chamber 3, and is properly secured to the bolster-plate. 4 the detachable and renewable forming- 40 ring supported on the bolster and secured thereto by an annular clamping-member 5 and screw bolts 6. The forming-ring is provided with a concentric projection 7, which engages a like seat 8 in the bolster.

45 On the upper face of the member 5 is an annular cutting member 9, which assists in cutting the stock, and the inner upper edge of the forming-ring 4, is slightly rounded to facilitate the entry of the blank to the 50 interior of the forming-ring and prevent tearing or breaking; and within the forming-ring is a vertically movable follower-die 10 resting on a support 11, which is spring actuated to raise the follower-die after each 55 down stroke of the forming-die, and to sus-

tain the follower-die while the annular groove 12 is being formed in the closure or cap 13. The spring is omitted from the drawings, as it is well known in this class of machines, and forms no part of my invention. 60

In the upper end of the follower-die is an annular rabbet 10', and a passage 14, which passage is continued down into the support 11 to release confined or trapped air under the blank 15, shown in position in Fig. 1. 65

16 indicates a vertically movable die-head, to which is secured a die-plate 17, by bolts 18, and to which plate is attached a blank cutting-die 19, by bolts 19', which die in conjunction with the member 9, cuts out a 70 blank 15 at each consecutive stroke of the die-head.

20 indicates the forming-die supported in the die-head 16, and is attached to a vertically movable member 21, extending from 75 the plunger 22, and is provided at its lower end with an annular projection 23, which with the rabbet 10' forms the annular groove 12 in the closure 13. The forming-die is provided with a passage 24, which performs a two-fold function, first, in the down stroke of said die, it allows the escape of entrapped air between the face of the die and the blank 15, and also provides for displacing the completed closure 13 from 80 the face of the die, by an air blast, as will hereinafter be further described. 85

25 indicates an annular stripper surrounding and engaging the cutting-die 19, whose function is to strip the stock from the blank 90 cutting-die 19 after each down stroke of the machine, and is resiliently supported on bolts 26, and actuated by springs 27, secured to the die-plate 17. The stripper is brought into use with each up stroke of the die-head 95 and the cutting-die 19.

28 indicates an air supply pipe, provided with lateral extensions 29 and 30, the former being supported on the head 16 and is provided with a sleeve 31, preferably held to 100 its seat or in engagement with the pipe 28, by a coiled spring, not shown, to effect a tight joint between the end of the sleeve and said pipe, and supplies a blast of air to disengage the closure from the forming-die 105 20, as shown in Fig. 3, and the latter extension supplies a blast of air for removing the closure or cap 13 laterally from the machine, as shown in Fig. 4. The supply of air is intermittent and is controlled auto- 110

matically by means, not shown, operated from moving parts of the machine. The pipe 28 is provided with a port or discharge passage 28' with which the pipe 29 5 and its sleeve 31 engage as the head 16 rises, to disengage the closure from the die 20.

The forming-ring 4, is subject to great wear by frictional contact with the stock, and requires frequent renewal, and is therefore made detachable from the bolster 2, 10 and is made of hard metal.

In the operation of the machine, the stock is fed automatically on the upper surface of the bolster 2, the head 16 descends, and 15 the blank 15 is cut out by the combined action of the die 19 and the annular member 9. The forming-die 20 then continues its down stroke and performs the initial step in forming the groove 12 in the closure 20 13, then forces the blank into the forming-ring 4, and bends the blank into the form shown in Figs. 2, 3 and 4, as the follower-die 10 recedes or descends under pressure of the die 20 and against the resistance of 25 the spring, and when the follower-die reaches the lower end of its stroke, the closure has been completed. The machine then reverses its action, and as soon as the cutting-die 19 leaves the member 9, the stripper 25 automatically pushes off the stock from which 30 the blank 15 has been previously cut; and when the forming-die 20 reaches the upper end of its stroke, a blast of air from pipe 28 and branch 29, displaces the closure 13 35 therefrom, as shown in Fig. 3, immediately after which the closure is blown out laterally across the bolster, by a blast of air, from the branch 30 and is conveyed to a suitable receptacle, or preferably directly to 40 a receptacle in which the closures are immersed in paraffin.

It is obvious that the device may be used for cutting blanks and forming closures or caps from other material than paper, and is 45 therefore not limited thereto in its use.

Having thus fully described my invention, what I claim is—

1. In a machine of the class described, means for cutting blanks and forming closures or caps, comprising a cutting die, a 50 resilient annular stripper surrounding and engaging the cutting-die for removing stock therefrom, a fixed bolster, a removable forming ring, a movable forming die, and a following lower-die movable in said forming ring.

2. In a machine of the class described, means for cutting blanks and forming clo-

sures or caps, comprising a cutting die, a resilient annular stripper surrounding and engaging the cutting die for removing stock 60 therefrom, a fixed bolster, a removable forming ring, a movable forming die, and a following lower-die movable in said ring, means for conducting a blast of air for releasing the closure from the forming-die, and a separate air blast for discharging said closure from the machine.

3. In a machine of the class described, a fixed support, a bolster on said support, a die vertically movable in said bolster, provided with means for allowing escape of trapped air, a vertically movable head, a cutting-die secured thereto, a vertically movable forming-die concentrically arranged in said cutting-die, adapted to enter said bolster and provided with a passage for air, and a vertically movable annular stripper concentrically arranged on said cutting-die.

4. A machine of the class described, comprising a die-head, a cutting-die secured to 80 the head, a vertically movable forming-die, a forming-ring, a follower-die, said forming-die and follower-die being vertically movable in said forming-ring, an annular stripper surrounding and engaging the cutting-die, means for releasing trapped air in 85 the forming-die, and means for supplying a blast of air through the forming-die, means for releasing trapped air in the follower-die, and means for supplying a blast of air between the cutting-die and the upper face of 90 the bolster for discharging closures laterally from the machine.

5. A machine of the class described, comprising a die-head, a cutting die secured to 95 said head, a forming-die vertically movable in said cutting-die, and provided with means for releasing trapped air and supplying a blast of air for removing a cap therefrom, an air supply pipe having a branch slidably 100 mounted thereon for supplying air to said forming-die, a bolster, a forming-ring, a movable follower-die provided with means for releasing trapped air, and means for supplying a blast of air between the cutting-die and the upper face of the bolster for 105 discharging caps laterally from the machine.

In testimony whereof I affix my signature, in presence of two witnesses.

JOSEPH T. BOND.
